(57) **CLAIM**

The ornamental design for a razor handle, as shown and described.

DESCRIPTION

FIG. 1 is a perspective view of a razor handle of the present invention;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The broken lines that connect the solid claimed lines in FIGS. 1 and 2 define the bounds of the claim for the top surface of the razor handle. All other broken lines represent the environment of the claimed design. None of the broken lines forms a part of the claimed design.
